UNITED STATES PATENT OFFICE.

DAVID F. HALSTED, OF BROOKLYN, ASSIGNOR TO HIMSELF AND GILBERT H. FINGER, OF NEW YORK, N. Y.

JERSEY-WAIST.

SPECIFICATION forming part of Letters Patent No. 339,406, dated April 6, 1886.

Application filed December 19, 1885. Serial No. 186,196. (No model.)

To all whom it may concern:

Be it known that I, DAVID F. HALSTED, of Brooklyn, in the county of Kings and State of New York, have invented certain new and 5 useful Improvements in Ladies' Jersey-Waists, of which the following is a full, clear, and exact description.

Reference is to be had to the accompanying drawings, forming part of this specification, in 10 which similar letters of reference indicate corresponding parts in both the figures.

Figure 1 is a front elevation of a lady's jersey-waist to which my improvement has been applied, parts being broken away. Fig. 2 is 15 a cross-section of a part of the same, taken through the line $x x$, Fig. 1.

The object of this invention is to provide ladies' jersey-waists constructed in such a manner that their fronts can be readily 20 moved, washed, and replaced.

The invention consists in the construction and arrangement of parts, as will be herein-after fully described and claimed.

A represents a jersey-waist, which is made 25 of a knitted fabric in the ordinary manner. The adjacent edges of the forward part of the waist A do not meet, and are connected by a front, B, of woven fabric, the side edges of which are secured to the side edges of the jersey-waist by buttons C, attached to the said 30 front B, and which button into button-holes D, formed in the edges of the said waist A, or by hooks and eyes, or by other suitable fastenings. The opening in the forward part of 35 the jersey can extend the whole length of the garment or for a part of the said length, as may be desired, the front B being made of a corresponding length. With this construction, should the woven fabric front become soiled, it 40 can be readily detached, washed, and re-

placed, so that the front of the waist can be kept clean.

I am aware that a child's blouse having the usual row of buttons and button-holes along-side its meeting edges has been provided with 45 a detachable front having rows of hooks on its vertical edges that engage parallel rows of eyes at opposite sides of the meeting edges of the blouse; also, that knit Cardigan jackets are not new, and I do not claim the same as of my 50 invention; but I am not aware that a jersey has ever been formed with its adjacent edges separated by and detachably connected to the side edges of a piece of woven fabric. The jersey, as is well known, is a very elastic and 55 close-fitting garment, and tends to contract when properly fitting a person, so that when the front B is in place it is drawn evenly at its side edges to fit the contour of the wearer's body. If knit fabric were used for the detachable front, it would be drawn or stretched laterally, which would shorten its length and make an ill-fitting garment; but such is not the case with a woven fabric, as the jersey material cannot stretch it, while it will adapt it- 60 self to the form of the body, as before stated.

Having thus described my invention, what I claim as new, and desire to secure by Letters Patent, is—

A knitted jersey having a space between its 70 front edges and a separate woven fabric front having approximately the contour of the said space and detachably connected at its side edges to the front edges of the jersey, substantially as set forth.

DAVID F. HALSTED.
